DEVICE FOR CONTROLLING CARBURETORS
OF INTERNAL COMBUSTION ENGINES IN
AIRCRAFT

René Tampier, Boulogne-sur-Seine, France

Application June 25, 1938, Serial No. 215,937
In Great Britain July 6, 1937

7 Claims. (Cl. 74—471)

This invention relates to a device for controlling carburetors of internal combustion engines in aircraft.

It is necessary in connection with aircraft engines to provide means for preventing the pilot, when landing, from closing the throttle of the carburetor without enriching his mixture of petrol and air, for which purpose it has been proposed to provide means for interconnecting the handles 5 of the control levers so that the mixture lever is brought back with the throttle lever.

Further, for the purpose of being able to supply a very rich mixture in case of emergency when the throttle is fully open, means have been 15 added to the interconnecting means above referred to, adapted to push the mixture lever back to the "rich" position in an opposite direction.

The foregoing arrangement is open to the objection that one of the handles moving through 20 a small angle has sometimes to move a second handle through a larger angle, and the effort increases to great proportions.

On some carburetors the mixture lever has only two positions, one for the provision of a 25 rich mixture and the other for a weak mixture. This is usually effected by the opening and/or closing of taps.

The above named arrangement, however, is open to certain objections, for although means 30 have been provided for indicating to the pilot the correct movements to be made, it is possible for the lever to be left inadvertently in a dead position between the open and closed position of the taps.

The object of the present invention is to provide means for overcoming these objections.

With this object in view according to the present invention a control device for carburetors of internal combustion engines comprises a mixture control member having two operating positions, a throttle control member movable independently of the mixture control member, means for locking the mixture control member in at least one of its operating positions, said means comprising a spring-pressed catch which comes into operation to lock the mixture control member in a predetermined relative position of the throttle and mixture members, means operable by movement of the throttle control member for unlocking the mixture control member when the latter is in said locked position, alternative means operated independently of said throttle control member for unlocking the mixture control member in said locked position and comprising a member slidably mounted relatively to the mixture control member, and adapted to act directly on the spring-pressed catch, and spring means for automatically returning the mixture control member when it is unlocked, into its second operating position.

In the accompanying drawings which illustrate this invention—

Figures 1, 2 and 3 are sectional side elevations showing diagrammatically one embodiment with the parts in different positions as hereinafter described; 5

Figure 4 is a view, similar to the preceding figures, of a modification with the parts in the position corresponding to Figure 1, and,

Figures 5 and 6 are side elevations showing another embodiment with the levers in a position corresponding to that of Figure 1 and to that of Figure 2 respectively, and,

Figure 7 is an end elevation of Figure 5.

Referring first to Figures 1 to 3, the device 15 (which will be described as being disposed horizontally) comprises a box-like structure 1, the end plates 2, 2 of which are each furnished with two bearings in and through which two spindles 3, 4 (hereinafter referred to as the throttle spindle 20 and the mixture spindle respectively) disposed parallel with each other, are adapted to slide. The throttle spindle 3 is round in cross section at its ends where it slides in the end bearings, but its middle portion is reduced in size and is 25 cut away on one face to form a recess 5 with inclined or ramp ends while that part of said spindle opposite said recess is cut away to form a recess 6 of slightly greater length provided with square ends. A plunger 7 is secured in the middle of the box, the axis of said plunger being disposed at right angles to the axis of the spindles; one end of said plunger may be fork-shaped and the reduced part of the throttle spindle 3 is arranged to slide between the two legs, a pin or 30 roller 8 being secured across the open end of the fork, which pin or roller is adapted to bear on that face of the spindle having the recess 5 with the angularly disposed ends. The opposite end of the plunger is provided with a collar 40 or enlarged head 9 between which and the fixed part in which said plunger is slidably mounted, is a coiled spring 10 which serves to maintain the pin or roller 8 in contact with the adjacent face of the throttle spindle. The mixture spindle is 45 composed of a tube 4 within which is telescopically arranged a smaller tube 11, the outer end of which is connected to the mixture lever. The larger tube 4 is provided with an aperture 12 and a conical recess 13 suitably spaced apart 50 with which the free end of the plunger 7, provided with a conical end, is free to engage. The larger tube is adapted to contain a coiled spring 14, one end thereof being arranged to bear against an abutment 15 fixed relatively to the 55 end of the box 1 by a pin 16 passing through longitudinally disposed slots provided in the tube and the other end against an abutment 17 fixed to the tube 4, which abutment is provided, on the opposite face to that against which the 60

spring bears, with a longitudinally disposed spindle 18 of reduced diameter, which is adapted to slide in the inner end of the smaller tube 11, the extreme end of said spindle being provided 5 with an enlarged collar 19. The inner end of the smaller tube 11 is provided with a conical portion 20 adapted to coact with the conical end of the transversely disposed plunger 7 when the latter has entered the aperture 12 in the larger 10 tube.

The operation of the device is as follows:

Assuming the throttle and mixture levers are at the left-hand side of the box 1 and that both spindles are also in their extreme left-hand positions as shown in Figure 1, the throttle lever is 15 in the closed position and the mixture lever in the normal position with the spring 14 in the mixture spindle fully expanded. The pin or roller 8 on the transverse plunger 7 is resting on the higher portion of the throttle spindle 3 on 20 the right of the recess 5 with the inclined ends while the lower conical end thereof is engaging in the conical recess 13 in the tube of the mixture spindle, which recess is of smaller diameter 25 than the aperture 12 on the left. This is a suitable position for the parts when landing the aircraft, and in this position it is impossible to move the mixture spindle 4 as the plunger 7, by reason of the position of the throttle spindle, cannot 30 rise. For cruising purposes the throttle lever is actuated to move the spindle 3 to the right into its mid-position shown in Figure 2 so that the pin or roller 8 on the plunger is caused to enter the recess 5 in said spindle. As in this position 35 the plunger 7 is capable of being pushed upwardly owing to the recess 6, the mixture spindle may now be moved to the right until the lower end of the plunger 7 enters the aperture 12 in the tube with the spring 14 therein fully 40 compressed and the conical part 20 of the piston on the end of the small tube 11 disposed to the right of the conical end of the plunger as shown in Figure 2. If the throttle lever is now moved still further to the right the plunger 7 45 is raised by the inclined end of the recess 5 and under the load of the spring 14 the edge of the aperture 12 forces the conical end of the plunger 7 completely out of the tube which thereupon returns automatically to its normal position 50 shown in Figure 3. Should this sequence not take place with sufficient speed due to friction in the parts connected thereto and to the carburetor, or if the pilot has to move his mixture lever to the other position, he can himself effect the same 55 result by moving the handle attached to the mixture spindle. In this case the small tube 11 is caused to move to the left without moving the large tube 4, the latter being locked by the plunger 7, and the conical part 20 on the end 60 thereof forces the end of the plunger outwardly, thereby releasing the parts as above described. The larger tube will be pushed in the same direction as the small one by the spring 14.

For maximum cruising speed to take off, the 65 mixture spindle being in its extreme left-hand or normal position, the throttle spindle 3 is pushed still further to the right into the open position as shown in Figure 3. In this position of the spindles as the portion of the plunger 7 at the 70 lower ends of the forks is resting on the lowest portion of the spindle 3 on the left of the recess 6, the plunger cannot rise and the lower end thereof is engaging with the conical recess 13 in the tube of the mixture spindle which is thereby 75 locked in this position as shown in Figure 3.

Referring to Figure 4 the recess 6 in the throttle spindle shown in Figures 1 to 3 is eliminated and the larger tube 4 of the telescopic members of the mixture spindle is furnished with only one aperture 12 with which the free end of the plunger 7 is adapted to engage. The plunger instead of being positively controlled by the throttle spindle 3 is shaped so that it can only lock the mixture spindle when the recess 5 with the inclined or ramp ends and the mixture spindle 10 are in such a position to enable the plunger to engage with the single aperture 12 in the larger tube 4 of the mixture spindle.

The operation of the device as above described 15 is as follows:

Assuming the throttle and mixture levers are at the left-hand side of the box 1 and that both spindles are also in their extreme left-hand positions as shown in Figure 4, the throttle lever will be in the closed position and the mixture 20 lever in the normal position with the spring 14 in said spindle fully expanded. The free end of the plunger 7 will be resting against the outer face of the tube 4, the pin or roller 8 of said plunger being held just out of contact with the 25 throttle spindle 3 on the right of the recess 5.

In this position it is possible to move the mixture spindle through its complete range, but it cannot be left in the weak position by the pilot as the plunger 7 is held back from engagement 30 with the aperture 12 by the throttle spindle 3 and the returning action of the compression spring 14 will return it to the normal position. If the mixture lever is not moved from the extreme left-hand position it is possible to move 35 the throttle spindle 3 through its complete range of movement without affecting the position of the plunger 7. If, however, the throttle spindle is moved to its mid-position so that the pin or roller 8 on the plunger is free to enter the 40 recess 5 in the spindle and the mixture spindle is also moved to the right, then when the aperture 12 in the tube 4 of the mixture spindle coincides with the plunger 7, the latter will enter the aperture and will be held until disengaged 45 by the conical member 20 inside the mixture spindle or by further movement of the throttle spindle. This simplification prevents the plunger 7 from being jammed between the two spindles if the throttle spindle is moved faster than the 50 mixture spindle when it is returned by the compressed spring 14.

In the modification shown in Figures 5, 6 and 7, 55 21 is the mixture lever, 22 the throttle lever, the former of which is controlled by a spring 23. The mixture lever 21 is provided with a spring controlled slide member 24 furnished at its lower end with a laterally disposed roller 25, and at its upper end with a knob 26. The throttle lever is provided with a cam member 27 having a recess 28 with which the roller 25 co-operates. The movement of the mixture lever 21 to the weak position shown in Figure 6 is limited by a stop 29 having a recess 30 with which a catch 31 on the slide member 24 is adapted to engage. 60

In Figure 5 the throttle lever is in the closed position and the mixture lever is in the normal position, and in Figure 6 the mixture lever is in the weak position and the throttle lever in the 70 cruising position. In the position of the parts as shown in Figure 6 the roller 25 is disposed in the recess 28 in the cam plate 27, thus permitting the slide 24 to move upwards and bring the catch 31 thereon into engagement with the re- 75

cess 30 in the stop 29 to lock the mixture lever in the weak position; in this position of the parts the throttle lever is permitted to have a small movement corresponding to the extent by which 5 the length of the recess 28 exceeds the diameter of the roller 25. It will be seen that in any other relative positions of the mixture and throttle levers the same plate will co-operate with the roller to prevent the locking of the mixture 10 lever. The mixture lever may also be released from the weak position by depressing the knob 26 on the slidable member 24 of the mixture lever.

What I claim is:

15 1. A device for controlling carburetors of internal combustion engines, comprising throttle and mixture levers in combination with a spring controlled slidable catch member carried by the mixture lever, a stop having a recess with which 20 said catch is adapted to engage, a laterally disposed roller on said member, and a cam member on the throttle lever, said cam member having a recess with which said roller co-operates so that the catch can engage with its recess to 25 lock the mixture lever when the two levers occupy a predetermined relative position.

2. A control device for carburetors of internal combustion engines comprising a mixture control member having two operating positions, a throttle control member movable independently of the mixture control member, means for locking the mixture control member in at least one of its operating positions, said means comprising a spring-pressed catch which comes into operation to lock the mixture control member in a predetermined relative position of the throttle and mixture members, means operable by movement of the throttle control member for unlocking the mixture control member when the latter is in said locked position, alternative means operated independently of said throttle control member for unlocking the mixture control member in said locked position and comprising a member slidably mounted relatively to the mixture control member, and adapted to act directly on the spring-pressed catch, and spring means for automatically returning the mixture control member when it is unlocked, into its second operating position.

50 3. A control device according to claim 2 wherein in the spring-pressed catch comprises a spring-pressed bolt, said throttle control member being provided with at least one recess in its surface and being mounted for sliding through said bolt, the mixture control member extending parallel 55 to the throttle control member and having an aperture which, in one operating position of the mixture control member is directly below said bolt, the arrangement being such that when the 60 mixture control member is in the said one operating position and the recess in the throttle control member is in line with said aperture in the mixture control member, the bolt is free to move under the action of its spring to engage 65 the aperture in the mixture control member.

4. A control device according to claim 2 wherein in the spring-pressed catch comprises a spring-pressed bolt, the said throttle control member being provided with at least one recess in its surface and being mounted for sliding through said bolt, the mixture control member extending parallel 70 to the throttle control member and having

an aperture which, in one operating position of the mixture control member is directly below said bolt, the arrangement being such that when the mixture control member is in the said one operating position and the recess in the throttle control member is in line with said aperture in the mixture control member, the bolt is free to move under the action of its spring to engage the aperture in the mixture control member, and the means operable by movement of the throttle control member for unlocking the mixture control member comprises raised surfaces on each side of the recess in the throttle control member, acting, when the said member is moved axially, to raise the bolt out of engagement with the aperture in 15 the mixture control member, whereupon the latter member is returned by a spring to its other operating position.

5. A control device according to claim 2 wherein in the spring-pressed catch comprises a spring-pressed bolt, said throttle control member being provided with at least one recess in its surface and being mounted for sliding through said bolt, the mixture control member extending parallel to the throttle control member and comprising two telescopic members, the inner member being connected to the mixture lever and the outer member formed with an aperture which, in one operating position of the mixture control member, is directly 20 below said bolt, the arrangement being such that when the mixture control member is in the said one operating position and the recess in the throttle control member is in line with said aperture in the mixture control member, the bolt is free to move under the action of its spring to engage 25 the aperture in the mixture control member, means for disengaging the bolt from the aperture comprising raised surfaces on each side of the recess in the throttle control member acting, when the said member is moved axially, to raise 30 the bolt out of engagement with the aperture in the mixture control member, together with alternative means for disengaging the bolt from the said aperture comprising the said inner member of the mixture member which is arranged 35 to act directly on the said bolt and press it outwardly against its spring.

6. A control according to claim 2 wherein the said means for locking the mixture control member are effective in two operating positions, the 50 said mixture control member having two apertures arranged respectively to be engaged by the spring-pressed catch in the two operating positions of the mixture control member.

7. A control device according to claim 2 wherein in the spring-pressed catch comprises a spring-pressed bolt and the mixture control member extends parallel to the throttle control member and comprises two telescopic members, the inner member being connected to the mixture control lever and the outer member formed with two apertures adapted to be engaged respectively by the spring-pressed bolt in the two operating positions of the mixture control member, the 55 said inner member being arranged for direct operation by the operator to disengage the spring-pressed bolt from one of said apertures, thereby 60 allowing the mixture control member to be moved automatically by the spring means to its other 65 operating position.
